UNITED STATES PATENT OFFICE.

GEORGE H. HILL, OF SCHENECTADY, NEW YORK, ASSIGNOR TO GENERAL ELECTRIC COMPANY, A CORPORATION OF NEW YORK.

AUTOMATIC CONTROL FOR FLASH-BOILERS.

1,190,167.

Specification of Letters Patent.

Patented July 4, 1916.

Application filed May 25, 1915. Serial No. 30,444.

To all whom it may concern:

Be it known that I, GEORGE H. HILL, a citizen of the United States, residing at Schenectady, county of Schenectady, State 5 of New York, have invented certain new and useful Improvements in Automatic Control for Flash-Boilers, of which the following is a specification.

My invention relates to electric water 10 heaters and has for its object the provision of means whereby the temperature and flow of water in such devices may be controlled in a reliable and efficient manner.

My invention relates more specifically to 15 water heaters for generating steam, and more particularly to water heaters of the type known as flash boilers in which steam is generated rapidly. In a flash boiler, water is forced through passages such as pipe 20 sections which are heated to a relatively high temperature so that steam will be generated almost instantly when the water touches the heated surfaces. When electric energy is used for heating the water by passing the 25 electric current through the pipe, it is necessary that the pipe be of a considerable length in order to obtain sufficient electrical resistance. A high pressure is therefore required to force the water through the pipe, 30 and to overcome this difficulty, it has heretofore been proposed to divide the pipe into sections connected in parallel with reference to the water supply so that the water may be pumped through each section independently of the others, each section having its 35 own inlet and discharge connections. Such a heating system is disclosed in a patent to Batchelder No. 1,019,413 which was issued March 5, 1912.

40 One of the difficulties encountered in such a system is that the delivery of water to the various sections is not always uniform. This is due to mechanical differences in the various pumps, to the presence of air in the water, or to various other causes. The result 45 is that when the amount of water delivered to one section becomes less than that delivered to the other sections, the section becomes heated more than the other sections and in time becomes overheated, since overheating of a section causes an increase in steam pressure in that section, which in turn causes a still smaller amount of water to be delivered to this section. The action thus

becomes cumulative and a section is liable 55 to be burned out.

In accordance with my invention, provision is made for counteracting the tendency of any of the sections toward becoming overheated, by providing means controlled by 60 the temperatures of the various sections for controlling the relative rates of delivery of water from the source of supply to the various sections so as to equalize the temperature of all of the sections. 65

For a fuller understanding of my invention, reference may be had to the accompanying drawings, in which—

Figure 1 is a diagrammatic view showing the preferred form of my invention; 70 Fig. 2 is a sectional view of the valve controlling the by-pass in Fig. 1; Fig. 3 is a diagrammatic view similar to Fig. 1, showing a modification of my invention; Fig. 4 is a sectional view of the valve controlling 75 the by-pass of Fig. 3; Fig. 5 illustrates still another modification, and Fig. 6 is a sectional view showing a valve applicable to the system there illustrated.

Referring, now, to the drawings, and first 80 to Fig. 1, A is a flash boiler composed of a plurality of pipe sections 10, 11, 12, and 13, which are insulated from each other at 14, and are provided with inlets 15, insulated from the pumps at 16. Separate outlet pipes 85 17 are also provided, which communicate with a delivery pipe 18 by means of a pipe 19 which is insulated from the outlet pipes 17 as indicated. A tank 20 constitutes the source of water supply from which water is 90 fed to the various pipe sections by means of pumps 21, 22, 23, and 24. The pumps are operated through suitable gearing 27 by a motor 25 connected to the line 26.

The system thus far described is the same 95 as that disclosed in the Batchelder patent above referred to, and no novelty is claimed therefor.

In order to overcome the difficulties which have heretofore been experienced as above 100 outlined, I provide relays 28, 29, 30 and 31, one for each heater section. These relays are made responsive to the temperature of the various sections of the heater by providing each relay with a coil connected across 105 a heater section so that the rise in temperature of the section will, by increasing the voltage drop across the section, cause the

relay to operate. In order that the relays shall not be affected by variations in voltage, I also provide each of them with a coil connected to the main source of potential 5 and which is differentially wound with respect to the other. As illustrated, therefore, relays 28, 29, 30 and 31 each comprises two windings, the lower winding being a potential winding connected across the line 10 while each upper winding is connected across a heater section. The potential windings are all in series and the arrangement of each relay is such that under normal conditions, the relays will be inoperative due 15 to the differential action of the two windings. Each of these relays controls a valve which in turn controls the supply of water to a heater section. In the particular arrangement shown, in Figs. 1 and 2 the relays control coils 36 which, when energized, open a normally closed valve 37 in a by-pass around the pump which feeds the section controlled by this particular relay.

The operation of this form of my invention is as follows: Normally the motor 25 will be operating continuously, driving the pumps 21, 22, 23 and 24. The by-passes around these pumps are closed and all of the heater sections are being fed alike. The 20 relays 28, 29, 30 and 31 are deenergized so that their switch arms are in engagement with the lower contacts which are connected with the various valve coils 36. If now, one of the pipe sections should become overheated, due to any cause, the voltage drop 25 across that part of the section is increased causing the relay controlled by this section to operate. Assuming for example, that the section 10 becomes overheated: the relay 28 will be operatively energized since the ampere turns of the upper winding will be increased, while the lower winding will be unaffected. The operation of relay 28, causes the switch arm 32 to engage its upper contact thereby completing the circuit from the line through switch arm 32 and thence in parallel through the switch arms 33, 34 and 35 which are in a lower position, to the three coils 36 controlling the valves 30 of the pumps 22, 23 and 24, delivering water to the sections 11, 12, and 13 respectively. The by-passes around the pumps 22, 23 and 24 are now opened, thereby causing these pumps to decrease the amount of water delivered by them to the sections 11, 12, and 13 and thereby raising the temperature of these sections. This causes the resistance and hence the voltage of these sections to be increased and this in turn decreases the 55 voltage drop across the section 10. The temperature of all of the sections is thereby equalized. It will be noted that with the differential arrangement of the relays any variation in line voltage will affect the two 60 coils of the relays equally so that the relays

will not be affected by any variation of line voltage, but will only be affected by the variations in the potential drop across the various heater sections which in turn will be governed by the temperature.

70

In Fig. 3, I have shown a modified form of the invention in which the desired result is produced by increasing the flow of water to the overheated section instead of decreasing the flow of water to the other sections. 75 The arrangement of heater sections and relays is the same as that of Fig. 1, but in this case, the by-pass around each pump is normally open so that under ordinary conditions, a certain amount of water is being 80 by-passed around each pump. When, therefore, a section becomes overheated, the relay associated with this particular section operates in the manner described in connection with Fig. 1. In this case, however, only 85 one winding 36 is energized to close a valve 37^a. For instance if the section 10 should become overheated, the relay 28 would operate to energize the coil 36 controlling the valve 37^a in the by-pass around the pump 90 21. This will cause the rate of delivery of water to section 10 to be increased.

90

In Fig. 5, I have illustrated another modification in which the water is delivered to the heater sections from a tank 20^a in 95 which the pressure is maintained constant. The tank is supplied from a pump 39 and an air dome 40 is provided for maintaining a predetermined pressure higher than needed to normally supply the boiler. In this case 100 the valves 37^b are located in the pipes leading from the tank to the various heater sections. The valves are normally closed by springs 41 and open at a predetermined difference in pressure between the tank and 105 boiler section to permit water to pass from the tank to the various sections.

100

The coils 36, one of which is energized by the operation of each of the relays, act upon the valves in opposition to the spring 41. 110 In the event of overheating of a section, the valve controlling the flow to that section will be opened by reason of the coil acting against the spring 41, thus allowing the full pressure of the tank into the section and thereby increasing the rate of delivery of water to the overheated section.

110

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by 123 other means.

123

What I claim as new and desire to secure by Letters Patent of the United States, is:—

1. An electric heating system comprising 128

a plurality of pipe sections in which the water is electrically heated, a source of water supply feeding said sections in parallel, and means for equalizing the temperatures 5 of all of the sections.

2. An electric heating system comprising a plurality of pipe sections in which water is electrically heated, a source of water supply for feeding said sections in parallel, and 10 electrically controlled means for varying the relative flow of water to these sections to equalize the temperature of said sections.

3. An electric heating system comprising a plurality of pipe sections in which the 15 water is electrically heated, a source of water supply feeding said sections in parallel, and means controlled by the temperature of a section for controlling the relative flow of water to the various sections.

20 4. An electric heating system comprising a plurality of pipe sections, a source of water supply feeding said sections in parallel, means for passing an electric current through said sections in series, and means 25 controlled by the temperature of any one section for controlling the relative flow of water to the various sections.

5. An electric heating system comprising a plurality of pipe sections, electric heating 30 means associated therewith, a source of water supply feeding said sections in parallel, and electromagnetic means controlled by the temperature of a section for controlling the flow of water to the various sections.

35 6. An electric heating system comprising a plurality of pipe sections in which the water is electrically heated, a source of water supply feeding said sections in parallel, and means comprising electromagnetic relays 40 provided with coils connected across the respective pipe sections for equalizing the temperatures of all of the sections.

7. An electric heating system comprising a plurality of pipe sections in which water 45 is electrically heated, a source of water supply for feeding said sections in parallel, electromagnetic relays controlled by the temperature of these sections, and valves controlled by said relays for controlling the 50 water flow to the various sections.

8. An electric heating system comprising

a plurality of pipe sections in which the water is electrically heated, each having a separate inlet, a separate pumping device connected with each inlet, by-passes around 55 the various pumps, and means controlled by the temperatures of the various sections for actuating said by-passes to vary the amount of liquid delivered to the various sections.

9. An electric heating system comprising 60 a plurality of pipe sections in which water is heated by the passage of current there-through, a source of water supply feeding said sections in parallel, and electromagnetic means jointly under the control of the 65 supply voltage and the voltage across the various sections for equalizing the temperatures in all of the sections.

10. An electric heating system comprising 70 a plurality of pipe sections in which water is heated by the passage of current there-through, a source of water supply feeding said sections in parallel, and means comprising differential relays whose coils are 75 jointly controlled by the supply voltage and the voltage across the various pipe sections, respectively, for equalizing the temperatures in all of the sections.

11. An electric heating system comprising a plurality of pipe sections, a source of 80 water supply feeding said sections in parallel, means for passing an electric current through said sections in series, and means jointly under the control of the line voltage and the voltages across the various sections 85 for controlling the relative delivery of water to the various sections, and thereby controlling their temperatures.

12. An electric heating system comprising a plurality of pipe sections in which water 90 is heated by the passage of current through the sections in series, a source of water supply feeding said sections in parallel, electromagnetic relays energized differentially by the supply voltage and the voltage across 95 the pipe sections and valves controlled by said relays for controlling the flow of water from the source to the various sections.

In witness whereof, I have hereunto set my hand this 24th day of May, 1915.

GEORGE H. HILL.
